UNITED STATES PATENT OFFICE.

CHARLES N. WALSH AND WILLIAM N. RUMELY, OF LAPORTE, INDIANA.

CENTRIFUGAL GOVERNOR.

No. 841,832.

Specification of Letters Patent.

Patented Jan. 22, 1907.

Application filed April 7, 1906. Serial No. 310,405.

To all whom it may concern:

Be it known that we, CHARLES N. WALSH and WILLIAM N. RUMELY, citizens of the United States, and residents of Laporte, La-
5 porte county, Indiana, have invented certain new and useful Improvements in Centrifugal Governors, of which the following is a specification.

This invention will be readily understood
10 from the following description, taken in connection with the accompanying drawings, in which—

Figure 1 is an elevation, part in vertical section, of governor parts exemplifying our
15 invention; Fig. 2, an elevation, part in vertical section, of one of the governor-balls and its immediate connections; Fig. 3, a horizontal section of a portion of the whirl, and Fig.
20 4 an elevation of the juncture of the gov-
ernor-rod and speeder-screw.

In the drawings, 1 indicates the valve-
body; 2, the housing surmounting the same;
3, a band at the base of the housing encircling
25 the top of the valve-body and capable of
turning thereon; 4, a set-screw through the
band engaging in a groove in the top of the
valve-body and serving to hold the housing
30 in place on the valve-body; 5, the valve-
stem projecting up into the housing from the
valve-body; 6, a hollow stud projecting rig-
idly upward from the top of the housing; 7,
35 a disk-like whirl mounted for rotation on the
stud above the housing; 8, the usual gearing
by which motion is transmitted to the whirl;
9, a collar secured to the stud above the whirl
40 and serving to prevent the whirl from rising,
this collar being secured to the stud by
means of a set-screw; 10, the governor-head
in the form of a disk mounted for rotation
45 and reciprocation on the upper end of the
stud; 11, the governor-balls; 12, radial
notches through the whirl, one notch for each
governor-ball; 13, a notch in the whirl in
45 the tangential line of each notch 12, a parti-
tion standing between the notches 12 and 13;
14, a horizontal pivot crossing each notch 12,
its head presenting itself in notch 13; 15, an
arm projecting rigidly downwardly from each
50 governor-ball, its lower end entering a notch
12 in the whirl and engaging the pivot 14
therein; 16, a band encircling and closely
fitting the whirl and closing the exterior of
the notches therein; 17, a pivot horizontally
55 crossing each governor-ball; 18, a gap in the
upper portion of each governor-ball, extending
from each end of its pivot 17 around the

upper portion of the ball and extending an-
gularly over a portion of the upper part of
the ball, the floor of the gap representing a
spherical convexity of smaller radius than
that of the ball; 19, a yoke disposed in the
60 gap of the governor-ball and having its ends
coupled to the pivot therein, the exterior
surface of the yoke corresponding substan-
tially with the spherical exterior of the ball
65 and the width of the yoke being such as to
permit it to have a proper amount of angular
play in the gap in the ball; 20, an arm pro-
jecting rigidly upward from each yoke; 21, a
pivot in the governor-head engaged by the
70 upper end of each of the arms 20, the provi-
sion of notches, pivots, and band for the
governor-head being substantially the same
as has been described in connection with
the whirl; 22 a hollow screw surrounding
75 the stud and inclosing collar 9, this screw be-
ing threaded downwardly into the whirl, the
upper end of the screw being cupped; 23,
ports through the wall of screw 22 to permit
access to the set-screw of collar 9; 24, a heli-
80 cal spring encircling the stud between the
whirl and the governor-head, this spring be-
ing compressed between the governor-head
and the adjusting-screw 22; 25, a cap car-
ried by the whirl above the upper end of the
85 stud; 26, the governor-rod fitted to slide ver-
tically through the stud, its lower end being
near the upper end of the valve-stem and be-
ing cut off at an angle, while its upper end
projects above the top of the stud; 27, a but-
90 ton on the upper end of the governor-rod
engaging under cap 25; 28, a coupling
screwed removably to the upper end of the
valve-stem and having in its top a socket in
which the foot of the governor-rod has sliding
95 engagement; 29, a feather engagement be-
tween the coupling and the foot of the gov-
ernor-rod to permit the governor-rod to slide
in the coupling without capacity for turning
therein; 30, a screw threaded diagonally up-
100 ward into the coupling, its axis intersecting
that of the governor-rod and its upper end
coming under the foot of the governor-rod,
the foot of the governor-rod and the top of the
speeder-screw 30 having a V-and-notch en-
105 gagement, as seen in Fig. 4; 31, a handle on
the lower end of screw 30 by means of which
the screw may be adjusted; 32 the usual gov-
ernor-rod lifter by means of which a weight
or spring presses the governor-rod upward
110 and keeps its top button in contact with the
cap, this lifter in the present case having

- forked engagement with the coupling; 33, a shank telescoping into the lower end of the speeder-screw 30 and splined therein; 34, a flexible shaft connected with shank 33; 35, a bearing carried by the band of the housing, and 36 a shaft journaled in the bearing 35 and connected with the flexible shaft.
- In the absence of the flexible shaft and its shank the speeder-screw 30 may be turned direct by means of its handle 31, its effect being when screwed upward to increase the distance between the button 27 and the governor-valve and when screwed downward to lessen that distance, the result being that provision is made for adjusting the speed of the governor. The interlocking juncture between the upper end of the speeder-screw and the foot of the governor-rod, as illustrated in Fig. 4, makes the speeder-screw self-locking at each quarter-turn. By adding the extension-shaft 36, connected with the speeder-screw, provision is made by which the speeder-screw may be operated from a distance. By disconnecting the valve-stem from the coupling and by properly releasing set-screw 4 the housing may be readily removed, carrying with it the general motion-work of the governor.
- The governor may be taken apart or dismantled with peculiar facility. By properly releasing set-screw 4, the flexible speeder extension being absent or disconnected, the entire upper portion of the governor may be removed from the valve-body, leaving the valve-stem and coupling in place. Again, by releasing the set-screw of collar 9 the entire rotating top portion of the governor may be removed, upwardly removed from the housing and stud and without necessarily disturbing the adjustment of any part. This facility for disassembling the parts is a great convenience in original construction, in packing and shipping, and in inspection, maintenance, &c.
- The arms formed with and pivoted to the balls are made as short as practicable, and the major portion of these arms join with the balls in forming the centrifugal elements of the governor. By gapping the balls and locating the yokes of the upper arms within these gaps the main portion of the mass represented by these arms is brought closer to the center of the balls than would otherwise be possible, the result being that the center of gravity of the centrifugal elements or the main effective portion of it is brought into practical coincidence with the center of gravity of the mass of the balls.

We claim—

1. A governor comprising a governor-ball with an arm to engage a pivot and having its periphery provided with a gap, a yoke arranged for swinging motion in said gap and provided with an arm for a pivot and having an exterior surface corresponding sub-

stantially with the spherical exterior of the ball, and a pivot uniting the extremities of the yoke to the ball, combined substantially as set forth.

2. A governor comprising a rotary disk 70 provided with radial notches and with notches to the side thereof, a pivot crossing each radial notch and presenting an end in the notch to the side thereof and engaging the partition between the two notches, and 75 a band encircling the disk and forming outer walls for the notches, combined substantially as set forth.

3. A governor comprising a stud, a whirl and governor-head mounted thereon, a collar on the stud above the whirl, a hollow screw inclosing the collar and threaded into the whirl, and a helical spring compressed between the governor-head and hollow screw and adjustable by means of said screw, combined substantially as set forth. 80

4. A governor comprising a valve-stem, a coupling secured thereto and provided with a socket in upward prolongation of the axis of the valve-stem, a governor-rod having its 90 foot fitted to slide in said socket, and a speeder-screw threaded diagonally upward into said coupling and having its upper end engaging under the foot of the governor-rod, combined substantially as set forth. 95

5. A governor comprising a valve-stem, a coupling secured thereto and provided with a socket in upward prolongation of the axis of the valve-stem, a governor-rod having its foot fitted to slide in said socket, and a 100 speeder-screw threaded diagonally upward into said coupling and having its upper end engaging under the foot of the governor-rod, the foot of the valve-rod being beveled at right angles to the axis of the speeder-screw, 105 combined substantially as set forth.

6. A governor comprising a valve-stem, a coupling secured thereto and provided with a socket in upward prolongation of the axis of the valve-stem, a governor-rod having its 110 foot fitted to slide in said socket, and a speeder-screw threaded diagonally upward into said coupling and having its upper end engaging under the foot of the governor-rod, the foot of the governor-rod being beveled at 115 right angles to the axis of the speeder-screw, and the engaging ends of the governor-rod and speeder-screw having concave and convex interengagements, combined substantially as set forth. 120

7. A governor comprising a valve-stem, a coupling secured thereto and provided with a socket in upward prolongation of the axis of the valve-stem, a governor-rod having its foot fitted to slide in said socket, and a 125 speeder-screw threaded diagonally upward into said coupling and having its upper end engaging under the foot of the governor-rod, and an adjusting-shaft flexibly connected with the speeder-screw and projecting out- 130

wardly from the general governor structure, combined substantially as set forth.

8. A governor comprising a valve-body, a valve-stem projecting upwardly therefrom, a housing having separable and swiveling connection with the top of the valve-body, rotary governor parts carried by the housing, a governor-rod extending downward from the rotary parts toward the valve-stem, a coup-

ling separably secured to the valve-stem and connecting it with the governor-rod, and speeder-adjusting mechanism carried by the coupling.
